CLAIM

The ornamental design for an air conditioner, as shown and described.

DESCRIPTION

The patent or application file contains at least one drawing executed in color. Copies of this patent or patent application publication with color drawing(s) will be provided by the Office upon request and payment of the necessary fee.

1. Air conditioner

1.1 : Front

1.2 : Left

1.3 : Right

1.4 : Top

1.5 : Bottom

1.6 : Perspective

Fig. 1.1 is front view; fig. 1.2 is left view; fig. 1.3 is right view; fig. 1.4 is top view; fig. 1.5 is bottom view; fig. 1.6 is perspective view; the rear view of the design product is not easily visible or invisible in use, and therefore omitted; the portion in red is not part of the claimed design.
